UNITED STATES PATENT OFFICE.

BERNARD H. MAY, OF CHICAGO, ILLINOIS.

PERAMBULATOR OR BABY-CAB.

1,113,672.

Specification of Letters Patent.

Patented Oct. 13, 1914.

Application filed May 12, 1913. Serial No. 767,096.

To all whom it may concern:

Be it known that I, BERNARD H. MAY, a citizen of the United States, residing at Chicago, in the county of Cook and State of Illinois, have invented a new and useful Improvement in Perambulators or Baby-Cabs, of which the following is a specification.

The present invention relates particularly to tops or canopies for baby carriages or the like; and the primary object of the invention is to provide a cheap and durable construction of improved form, which enables the canopy to be readily shifted from one end of the carriage-body to the other and adjusted in any desired position.

My invention is illustrated in its preferred embodiment in the accompanying drawings, in which:

Figure 1 is a side elevational view of a carriage-body and top applied thereto in accordance with my invention, the body and top being shown in skeleton form; Fig. 2, a cross-sectional view taken as indicated at line 2 of Fig. 1; and Fig. 3, a broken sectional view taken as indicated at line 3 of Fig. 1.

The construction illustrated comprises a carriage-body A; a pivotally-mounted U-shaped carriage-top support B; and a top or canopy C.

The carriage-body, in the form shown, comprises a substantially rectangular base frame or bottom 1 having a depressed central portion, or foot-rest, 1^a; and skeleton sides 2 and ends 3 supported on the frame 1. The upper portion of the body comprises a rod-form member which is suitably curved to form the side-pieces, or arms, 4 and end-pieces, 4^a.

The outer edges of the lateral members of the frame 1 are provided with notches or recesses 5 adapted to accommodate the arms of the member B. The member B is of U-shape, comprising arms 6 which are united at their lower ends by a web 6^a disposed beneath the carriage-body. The arms 6 extend freely through the notches 5, and are supported by pivots 7 carried by the side members of the frame 1. The upper ends of the arms 6 pass inside of the side-arms 4 of the carriage-body and are confined close to the side arms by guide-members 8 which are secured to the inner surfaces of the side-arms, as clearly appears from Figs. 2 and 3. Thus, there are provided slots or guide-channels 9 in which the arms 6 can swing. The

attaching screws 9^a afford studs or abutments for limiting the swing of the arms 6. On the upper side of each arm 4 of the carriage-body is secured, by a centrally disposed pivot 10, a reversible locking pawl 11 whose free end is provided with notches 11^a adapted to engage one edge or the other of the corresponding arm 6, depending upon whether the arms 6 are at one end of their guides or at the other.

The upper end portions of the arms 6 are curved outwardly over the members 4 of the body, as indicated at 6^b, and the extremities of the arms are turned downwardly as indicated at 6^c. The down-turned extremities 6^c afford brackets, or pivot-members, adapted for connection with the lower ends of the bows of the carriage-top or canopy.

In the form shown, the carriage-top comprises bows 12 which are firmly secured at their lower extremities to pivot-members 13. The pivot-members 13 are secured to the pivot-members 6^c by short bolts 14 equipped with winged nuts 15. By such means the carriage-top can be firmly clamped to the swinging or shiftable support B and disposed at any desired angle with relation thereto.

Fig. 1 shows the condition when the arms 6 are at one end of their guides, and the carriage-top is clamped to the arms so as to be supported independently. If desired, the nuts 15 may be loosened and the top may be allowed to drop over the end-portion of the carriage-body. When it is desired to shift the top to the other end of the body, this may be accomplished by turning the locking pawls 11 out of the way and swinging the member B on the pivots 7 until the arms 6 engage the studs 9^a at the other end of the guide-slots 9, when the arms can be locked in the new position.

While the carriage-body and top are shown in skeleton form, it will be understood that they may be covered with wicker-work. In the form shown, the sides of the body are provided with ratan rods or bows 16, the central portions of which are bowed downwardly so as to house the lower ends of the arms 6 and the depressed portion 1^a of the bottom of the body. It will be understood that when wicker-work is applied to the body the member B is rendered practically invisible, it being understood that the body is upholstered suitably inside. The only portions of the support

B which are exposed are, therefore, the upper portions 6^a and 6^c and these parts are usually nickelized or given some suitable finish.

5 The foregoing detailed description has been given for clearness of understanding only, and no undue limitation should be understood therefrom.

10 What I regard as new, and desire to secure by Letters Patent, is:

15 1. In means of the character set forth, the combination with a carriage-body, of a U-shaped support having a web disposed transversely below the carriage-body and arms extending upwardly at the sides of said body, top-attaching members provided at the upper ends of said arms, an independent carriage-top having coacting attaching members adapted to be secured to said arms, 20 and a pivotal connection between said U-shaped support and the lower portion of the carriage-body.

25 2. In means of the character set forth, the combination of a carriage-body provided with a bottom and with sides, guides at the upper portions of said sides, arms pivotally connected with the lateral portions of said bottom and extending upward through said guides, said arms having downwardly 30 turned ends affording top-attaching mem-

bers, and a top adjustably secured to said members.

3. In means of the character set forth, the combination of a carriage-body comprising a bottom and sides, guides at the upper portions of said sides, a U-shaped member comprising arms pivotally connected with the lateral portions of said bottom and a web uniting the lower ends of said arms below said bottom, said arms having their upper ends extending through said guides and curved outwardly and downwardly, and a carriage-top secured to the extremities of said arms.

4. In means of the character set forth, the combination of a body having a bottom and sides, said sides provided at their upper portions with guides, a U-shaped support comprising a web disposed beneath said bottom and arms extending upwardly and housed in said sides, the upper ends of said arms extending through said guides and equipped with top-attaching members, a top secured to said members, and pivots connecting said arms with the lateral portions of the bottom of said body.

BERNARD H. MAY.
